Inventor

Arsene J. Bouchard.

By Horatio E. Bellone

Attorney.

UNITED STATES PATENT OFFICE.

ARSENE J. BOUCHARD, OF PROVIDENCE, RHODE ISLAND.

BANJO.

Application filed July 10, 1925. Serial No. 42,715.

My invention relates to banjos and similar stringed instruments.

The essential objects of my invention are to enable the tightening of the head without moving the same out of the original plane of the finger board; to enable the tensioning of the head with accuracy; to facilitate the introduction and removal of the head; to accommodate the tail piece to the strings; to increase the volume and resonance of the instrument; and to strengthen the construction. Other objects and advantages will hereinafter be apparent.

To the above ends essentially, but not exclusively, my invention consist in such parts and in such combinations of parts as fall within the scope of the appended claims.

In the accompanying drawings which form a part of this specification

Figure 1 is a top plan view of a banjo or similar instrument embodying my invention,

Figure 2, a rear elevation of the same showing parts thereof broken away,

Figure 3, a fragmentary section on line 25 3—3 of Figure 2,

Figure 4, an enlarged side elevation of the rear end of the instrument,

Figure 5, a detail perspective of the pivoted portion of the wings, and

Figure 6, a perspective of the upper portion of the tail piece.

Like reference letters indicate like parts throughout the views.

In its present and preferred form my banjo has a body 10 comprising a broad metallic outer sectional hinged tension ring 11 composed of segments 12 hinged by pintles 14 in perforated lugs 15 upon the upper and lower portions of the forward end 40 of the segments. Adjacent the rear ends of the segments are lugs 17 having threaded perforations adapted to receive a binding screw 19. Above the lugs are corresponding lugs 21 provided with perforations 22, one of 45 which has a thread 23 to receive a thread 24 upon a bolt or pivot pin 25. The intermediate portion of the inner face of the ring 11 is provided with a broad annular recess 28 forming a resultant angular annular shoulder 29 upon the upper margin of the ring and a flange 30 upon its lower margin. The body 10 includes an inner broad metallic body rim 32 relatively to which the ring 11 moves. Upon an intermediate portion of

the former is an external annular shoulder 55 34 extending into the recess 28.

The usual head 36 is preferably of membrane, parchment, skin, or the like, with its margin extending between the body rim 32 and the side of the shoulder 29, and its skin 60 or flesh hoop 38 extending into the recess 28 and abutting against the bottom of shoulder 29. An annular series of perforations 40 vertically disposed in the flange 30 have threads 41 engaging the threads 42 of clamping screws 43 whose inner ends bear against the bottom of the shoulder 34 within the recess 28. By turning these screws the ring 11 is drawn downwardly relatively to the ring 32 and the head 36 is tightened. 70

A guide for the sound waves comprises an internal annular horizontal plate 45 fixed by solder or otherwise to the upper portion of the ring 32 spaced from the head, integral with those inner edge is a downwardly flaring wall 46 engaging the bottom portion of the ring 32. 75

The neck 48 has upon its outer end the usual peg head 49 carrying the tuning pegs 50. The top of the neck constitutes the usual finger board 51. The neck in this instance comprises an upper or body section 52 and a lower or base section 53 separated from each other by a metallic horizontally disposed tongue 54 integral with a curved attaching plate 55 fixed by rivets 56 to the inner face of the ring 32, and passing through an opening 57 in the latter and through a guide slot 58 in the outer ring 11. This slot permits adjustable vertical movement of the ring 11 relatively to the fixed ring 32. The base section of the neck and the body section are attached respectively to the tongue 54 by a screw 60 and bolts 61, in the base and body respectively. The tongue is provided with a threaded opening 62 for the screw 60, and with holes 63 for the bolts. 95

The tail piece consists of an angle plate 64 comprising a horizontal string attaching portion 65, and a depending free portion 66 100 and provided at the junction of the portions with a transverse hole 67 to loosely receive the pivot pin 25. In the portion 66 is an adjusting screw 68 whose thread 69 engages a thread 70 in a hole 71. The end of the screw bears against the body of the banjo. Above the hole 71 is a hole 72 through which extends a post or screw 73 upon the banjo body 105

which has a thread 74 to engage a check nut 75 engaging the outer face of the plate. The screw 73 is a check screw for holding the tail piece in adjusted position. The upper face of the portion 65 is provided with oblong recesses 77 separated by a partition 78 provided with transverse slots 79. Leading to the forward ends of the recesses 77 are horizontal slots 80 into which lead vertical longitudinal slots 81. In the rear portions of the depressions 77 are posts 83 for the reception of loops 84 upon the ends of strings 85 which pass through the slots 80 after admission through the slots 81. In Figures 1 and 3 the strings are shown so attached. In case the wires have knots 86 upon their ends instead of loops 84, the posts 83 are not used, but the end of the string after passing through the slot 80 is placed in a slot 79 with its knot 86, as shown in Figure 6, abutting against the side of the partition 78. The usual bridge 87 on the head supports the strings.

A sound box 88 has the usual wooden bottom or floor 89 and metal side 90. This is of greater diameter than the head of the banjo and is attached to a depending portion of the ring 32 by radially disposed screws 91 passing through holes 92 and 93 respectively in the side and rim, and covered in this instance with spacing sleeves 94, as shown in Figure 2.

A sound board is provided consisting of a wooden plate 96 resting upon a metallic spacing ring 97 upon the floor 89 of the sounding box. The plate is held in position by a pin 98 extending through the ring and through holes 99 and 100 in the centers of the floor and plate. Broad heads 103 and 104 upon the ends of the pin bear tightly against the floor and plate. The latter is capable of vibration by the sound waves which escape thence upwardly.

I claim:—

1. In a banjo, a body comprising an outer sectional hinged tension ring having an annular recess with spaced-apart shoulders, an inner body rim, the said ring being movable relatively thereto, the said rim having a shoulder extended into said recess, and means engaging the shoulder of the said rim to assist in securing the rim in cooperative relation with said ring.

2. In a banjo, a rim, a sectional hinged tension ring embracing the rim, a binding screw connecting the free ends of adjacent segments, an internal annular shoulder on the ring, a head extending between the rim and shoulder, a peripheral flesh hoop on the head below the shoulder, and a neck carried by the ring.

3. In a banjo, a body rim, a sectional hinged tension ring embracing the rim and transversely slidably thereon comprising segments pivotally connected with each other, a

screw connecting the ends of the ring, an internal annular shoulder on the ring, a head on the rim engaged by the shoulder, clamping screws carried by the rim supporting the rim, and a neck carried by the ring.

4. In a banjo, a body rim, an annular shoulder upon an intermediate portion of the rim, a vertically slidable ring provided with an internal annular recess to loosely receive the shoulder, an internal annular shoulder upon the upper margin of the ring, an internal annular flange upon the ring below the first mentioned shoulder provided with an annular series of threaded perforations, clamping screws in said perforations engaging the first shoulder, a head on the body rim extending between the ring and rim, a peripheral enlargement on the head below the second shoulder, and a neck carried by the inner rim.

5. In a banjo, the combination with the body, neck, and head, of a sound box of greater diameter than the body carried by the body, and a vibratory plate fixed in the bottom of the box and spaced therefrom.

6. In a banjo, the combination with the body, neck, and head, of a sound box comprising a floor and a side exterior of the body, members connecting the side and body, a spacing ring resting upon the floor centrally thereof, a plate resting upon the ring, and a pin passing through the ring fixed to the floor and plate.

7. In a banjo, a body rim, a ring provided with a slot, a head engaged by the ring, a plate fixed to the body rim, a tongue on the plate extending through the slot, a neck and a base below the tongue, and threaded members in the body and base engaging the tongue.

8. In a banjo, a body, a metal tongue carried by the body and a neck comprising a base attached to the bottom of the tongue and a body fixed to the top of the tongue and threaded means in the body and base engaging the tongue.

9. In a banjo, a body rim, a ring, a head engaged by said rim, a horizontal annular plate fast to the upper portion of the body rim spaced from the head, and a flaring wall fixed to the annular plate and to the bottom of the body rim.

10. In a banjo, a neck, a body, a head fixed to the top of the body, a horizontal annular plate carried by the body below the head, a flaring wall depending from the plate, a sound box mounted upon the body and extending below the body, and a plate in the sound box below the flaring wall and spaced from the bottom of the box.

11. In a banjo, the combination with the body, head and neck, of a tail piece upon the body, provided with depressions, with horizontal slots extending to the depressions, and with longitudinal slots extending to the

horizontal slots, and a longitudinal partition between the depressions provided with transverse slots.

12. In a banjo, a body, a neck, a head, 5 lugs on the body, a pivot pin in the lugs, an angular tail piece comprising a string attaching portion and a depending free portion, a hole in the free portion, an adjusting screw in the hole bearing against the

body, a hole in the free portion adjacent the first hole, a post on the body extending through the second hole and provided with a threaded end, and a nut engaging the threaded end of the post and bearing against the outer face of said free portion. 10

In testimony whereof I have affixed my signature.

ARSENE J. BOUCHARD.
